DESIGN FOR A TABLE-FOUNTAIN.

Design No. 16,451, dated January 5, 1886.

UNITED STATES PATENT OFFICE.

GEORGE BROWN, OF WASHINGTON, DISTRICT OF COLUMBIA.

DESIGN FOR A TABLE-FOUNTAIN.

SPECIFICATION forming part of Design No. 16,451, dated January 5, 1886.

Application filed November 7, 1885. Serial No. 182,153. Term of patent 3½ years.

To all whom it may concern:

Be it known that I, GEORGE BROWN, a subject of the Queen of Great Britain, residing at Washington, in the District of Columbia, have 5 invented and produced a new and original Design for a Table-Fountain, of which the following is a specification, reference being had to the accompanying drawing, forming part thereof.

10 My design consists of a table-fountain comprising a stepped base, dividing plinths thereon, an image (such as a winged boy) holding a jet-tube arranged upon said base, a surrounding colonnade, and an architrave and 15 surmounting dome, as I will now proceed to particularly set forth and claim.

The drawing shows in perspective my newly-designed table-fountain.

10 The base portion *a*, of any suitable shape, 20 but herein shown as polygonal, is provided with a series of steps, *k*, and rising from the base at the several corners thereof are plinths *c*, suitably ornamented with panels *c'*, which latter contain any fanciful design. The plinths 25 *c* sustain ornamental images, herein shown as lions *c'*, and the center of the stepped portion of the base contains a fountain, herein shown as an image, *d*, holding a jet. Pillars *e*, herein shown as four in number, are mounted upon 30 the base portion, said pillars being of any suitable shape in cross-section, and supporting capitals *f*, of such fanciful design as may be desired. An architrave, *g*, rests upon the capitals *f*, and is ornamented with medallions and such other trimmings as may be desired. A cornice, *h*, rests upon the architrave, statuettes *h'* being placed upon the corners thereof. A dome, *i*, rests upon the cor-

nice, and has mounted upon it an emblematical ornamentation, herein shown as a globe, *j*, 40 and an eagle, *j'*. Around the base of the dome *i* an ornamental crown is placed.

It is obvious that the component parts forming the herein-described table-fountain may be variously ornamented without departing 45 from the leading features thereof. It is also obvious that some of the elements may be omitted—as, for instance, the images *c'* and capitals *f*, thereby permitting the architrave to rest directly upon the pillars; the cornice 50 *h*, with its statuettes, thereby permitting the dome to rest directly upon the architrave; also, the emblematical ornamentation.

I claim—

1. The herein-described design for a table- 55 fountain, it having a stepped base portion, plinths *c*, projecting therefrom, the fountain *d*, pillars *e*, architrave *g*, and dome *i*, as set forth.

2. The herein-described design for a table- 60 fountain, it having the stepped base portion, plinths *c*, leading therefrom, the images *c'*, fountain *d*, pillars *e*, capitals *f*, architrave *g*, cornices *h*, dome *i*, and emblematical ornaments *j j'*, all as set forth. 65

3. In a design for a table-fountain, the stepped base, the pillars, the dome, and the fountain *d*, arranged below the dome, as shown and described.

In testimony whereof I have signed my name 70 to this specification in the presence of two subscribing witnesses.

GEORGE BROWN.
